UNITED STATES PATENT OFFICE

WILLIAM H. PARDEE, OF ANTIGO, WISCONSIN.

DESIGN FOR AN ANTIRATTLER FOR THILL-COUPINGS.

SPECIFICATION forming part of Design No. 33,027, dated July 31, 1900.

Application filed July 3, 1900. Serial No. 22,456. Term of patent 14 years.

To all whom it may concern:

Be it known that I, WILLIAM H. PARDEE, a citizen of the United States, and a resident of Antigo, in the county of Langlade and State of Wisconsin, have invented a new and original Design for an Antirattler for Thill-Couplings, of which the following is a full, clear, and exact specification.

Reference is to be had to the accompanying drawings, forming a part of this specification, in which similar characters of reference indicate corresponding parts in all the views.

Figure 1 is a perspective view of an antirattler for thill-couplings, showing my design. Fig. 2 is a cross-section of the same on the line 2-2 in Fig. 3, and Fig. 3 is a face view of the same.

The design in its entirety consists of a wear-plate A, having a concave face A', a shank

B, rising from a transverse cylindrical rod C, 20 having annular flanges D on the ends, the said shank having a notched lug E on the back, as is plainly shown in the drawings.

The leading features of the design consist of the wear-plate, the shank, the cross-rod, 25 and the lug on the back of the shank.

Having thus fully described my invention, I claim as new and desire to secure by Letters Patent—

The design for an antirattler for thill-couplings, as herein shown and described.

In testimony whereof I have signed my name to this specification in the presence of two subscribing witnesses.

WILLIAM H. PARDEE.
